UNITED STATES PATENT OFFICE.

HANNAH NORDMAN, OF SEATTLE, WASHINGTON, ASSIGNOR OF ONE-HALF TO EDELE M. JOHNSON, OF KING COUNTY, WASHINGTON.

DESIGN FOR A WARMING-OVEN.

50,627.

Specification for Design.

Patented Apr. 17, 1917.

Application filed May 31, 1916. Serial No. 100,971. Term of patent 3½ years.

To all whom it may concern:

Be it known that I, HANNAH NORDMAN, a citizen of the United States, residing at Seattle, in the county of King and State of Washington, have invented a new, original, and ornamental Design for Warming-Ovens, of which the following is a specification, reference being had to the accompanying drawing, forming part thereof.

Figure 1 is a front elevation of a warming oven. Fig. 2 is a plan view of same, showing my new design.

I claim;

The ornamental design for a warming oven, as shown.

HANNAH NORDMAN.
